ABSTRACT OF THE DISCLOSURE

An apparatus consisting of a magnetic member mounted onto a wall portion of the grinding chamber of a hammer mill, said magnetic member including a collector whereby metallic particles are withdrawn from feed material being processed within said chamber, said particles being retained by said collector.

BACKGROUND AND SUMMARY OF THE INVENTION

Particular reference is had to a hammer mill type of grinder processing various types of animal feeds including silage material. It is not uncommon for silage material and other feed grains stored or accumulated on a farm to be ground for feed to have metallic particles therein which may come from various sources on a farm and may be inadvertently picked up off the ground. Metallic particles in the grinding process caused damage to the hammers and may become so hot as to become a source of combustion. It is not unusual for such particles to start fires within the grinding chamber, spouts or bins.

Various means are used to remove metallic particles from the feed ingredients being processed within the grinder. No knowledge is had of an apparatus or device operating directly in connection with the grinding chamber of a mill to remove metallic particles with the commencement of the processing of the material therein.

It is an object of this invention therefore to provide simple and efficient means to remove metallic particles from feed material in the processing chamber as in a hammer mill.

It is another object of this invention to provide a magnetic member mounted onto the enclosure of a grinding chamber of a mill having means within said chamber to retain metallic particles attracted thereto.

More specifically it is an object of this invention in connection with the grinding chamber of a hammer mill to provide a magnetic assembly comprising a magnet mounted onto a supporting plate and adapted to be removably mounted over a suitable opening within the screen enclosure of said chamber whereby material being processed therein passes sufficiently close to said magnetic assembly to have metallic particles within said material effectively withdrawn therefrom and retained by said magnetic assembly.

These and other objects and advantages of the invention will be set forth in the following description made in connection with the accompanying drawings in which like reference characters refer to similar parts throughout the several views and in which:

FIG. 1 is a broken view in front elevation of a grinding chamber;

FIG. 2 is a fragmentary perspective view on a magnified scale showing detailed construction of the invention herein;

FIG. 3 is a broken view in front elevation of a modification of the invention herein; and

FIG. 4 is a view in front elevation showing another modification of the invention herein with an alternate portion of a portion thereof being shown in dotted line.

2**DESCRIPTION OF A PREFERRED EMBODIMENT**

Referring to FIGS. 1 and 2, a housing portion 10 of a feed mill is shown. No more supporting structure than this is believed necessary to be shown for an adequate disclosure of the subject matter of the invention herein. The invention may be adapted for use with various types of mills for grinding and/or processing material. The invention is here shown in connection with a conventional type of a hammer mill.

Said housing 10 comprises a front wall 12 having a cover opening 13 therein, a rear wall 15, side walls 17 and 18, a top wall 20, and a supporting base 23. Discharge means from said base are not here shown. The cover which is not here shown will be supported by hinges 25 carried on the leading edge of the side wall 18, and latching members 26 for said cover are indicated on the leading edge portions of the side wall 17.

Carried on the rear wall 15 as by being welded thereto and extending forwardly therefrom is a flange 30 supporting the rear side wall edge portion of a screen assembly 35 to be described. Said flange in the embodiment here presented defines the form of a tear drop in plan. The apex or upper portion of said flange is formed by an inverted V-shaped plate member 32 which is the full width of said screen assembly and substantially the full width of the interior of said housing 10. Said member 32 also is suitably secured to said rear wall as by welding.

Said screen assembly 35 comprises a screen 36 of suitable mesh having its inner edge portion disposed about and supported by said flange 30. Said screen stops short of the apex portion of said flange and terminal plate portions 36a overlying the adjacent end portions of said member 32.

Overlying said screen to hold the same in operating position is a rectangular frame member 39 of like width and having sufficient length to have its identical end portions 39a and 39b overlie the respective adjacent end portions of said plate member 32.

Said end portion 39a is formed to comprise a pair of laterally spaced axially apertured ears or hubs 39c having a shaft 40 journaled therethrough. A pair of spaced hangers 42 have hubs 42a formed at their lower ends to have said shaft disposed therethrough and have their upper ends 42b suitably pivotally secured to a rod 41 cantilevered forwardly of said rear wall 15. A T-type adjusting screw member 50 has a lower transverse cylindrical portion 51 between said hangers 42 having said shaft 40 extend therethrough. The tubular arm 52 of said screw member extending from said transverse portion is tapped to receive a threaded rod 53 which extends outwardly of the side wall 17 through a hub bearing 55 carried by said side wall 17 through a hub bearing 55 carried by said side wall and in which said rod is rotatably secured and locked from having axial movement. Said rod is rotated by a terminal crank 57.

The end portion 39b is identical to the end portion 39a and has like related structural elements and though not specifically described are indicated by like reference numerals with a prime added.

With reference to FIG. 2, the sides 60 and 61 of said inverted V-shaped member 32 adjacent its apex have rectangular openings therein. Opening 64 is shown in the side 61. The corresponding opening in the side 60 is merely indicated. Respectively overlying said openings are identical magnetic assemblies 66 and 67.

It will be understood that said magnetic assemblies may be variously formed comprising either electromagnets or permanent type magnets within the scope of the invention herein. The magnetic assembly 66 will be described as here presented. Said assembly comprises a rec-

tangular supporting plate 69 to overlie the opening in side 60. Said supporting plate has a pair of spaced transverse slots 69a and 69b therein. Underlying said plate 69 and secured thereto as by bolts 75, is a nonmagnetic plate member 77. A permanent horseshoe type magnet 79 of a size to have adequate drawing power is shown having its poles respectively seated in said slots 69a and 69b in engagement with said underlying plate 77. Said magnet is secured to said plate 69 by bolts 81. The word magnet is here used in a collective sense to include the individual magnets shown.

Magnetic assembly 67 is of identical structure as said magnetic assembly 66 and is not here described. The magnetic member thereof is indicated by the reference numeral 79'.

At either end of said plate 69 are retaining members comprising bars 84 abutting either end of said plate 69 with superposed plate members 85 overlying the adjacent edge portions of said plate 69 and having bolts 87 pass therethrough and into the underlying plate member to 10 removably secure said magnetic assembly.

Mounted onto a shaft 90 extending forwardly of said rear wall 15 substantially centrally within said screen assembly is a conventional hammer type grinder assembly consisting of a plurality of circular axially spaced plate members 92 having rotatable hammers 95 pivoted therebetween adjacent the peripheries thereof as shown. A cover will overlie the cover opening and conventionally will have an inwardly extending flange to underlie and support the adjacent or leading edge portion of the screen assembly.

OPERATION

It is not uncommon for feed material provided from the farm for processing to contain metal particles of various kinds. These constitute a hazard and are efficiently removed in the operation of the invention as here described.

Material to be processed will be fed into the grinding chamber in a conventional manner, such as through an opening in the rear wall thereof. The grinding assembly will spin the material about the interior of the chamber with the hammers 95 mixing and reducing the material to a size to be discharged from the chamber through the screen 36.

In being processed, the material passes sufficiently close to the magnetic assemblies 66 and 67 to have the metallic particles within said material attracted by the magnets 79 and 79'. Said particles are retained on the underside of the plate members 77 and 77'.

The hammers 95 have but very little clearance in their extended positions with respect to the screen 36. Sufficient clearance must be provided so that the metallic particles accumulated onto the plates 77 and 77' will not be disturbed by said hammers. The tear drop configuration in plan of the screen assembly herein disclosed provides such clearance. Thus the processed material is effectively cleared of metallic particles.

The metallic particles accumulated onto the plates 77 and 77' will be retained thereon throughout any given cycle of processing material. To remove such particles, the grinder will be stopped. The cover of the grinding chamber will be removed. A suitable receptacle will be inserted or held beneath the magnetic assemblies and the metallic particles will readily be scraped off the underlying surfaces of the plates 77 and 77' to be dropped into the receptacle. These steps are not here shown but are indicated to provide a complete description of the operation. It will be understood that if electromagnets are used, then they need only to be deenergized to have the accumulated metallic particles simply drop into an underlying held receptacle.

To remove the magnetic assemblies, the bolts 87 need only to be loosened to loosen the plate members 85 and the entire assemblies may simply be moved laterally off of the supporting inverted V-shaped plate member 32.

MODIFICATION

Referring to FIG. 3, a modification is shown of the magnetic assembly with respect to its mounting onto the screen assembly. Except for the changes noted hereinafter, the structure is identical to that above described.

The inverted V-shaped member corresponding to the member 32 has no openings in its sides and is indicated by the reference numeral 99.

10 The magnetic assemblies 100 and 101 comprise the magnets 79 and 79' respectively secured onto single underlying plate members 103 and 104 and will be secured thereto as by bolts 105.

15 Here the magnetic assemblies are hinged to the member 99. With reference to the magnetic assembly 100, a piano type hinge 106 has its flap portion 106a secured as by welding to the upper edge portion of the supporting plate 103 and its other flap portion 106b with an underlying spacer 106c is secured to the upper outer side portion of said member 99 adjacent its apex, as shown.

20 The other or lower end portion of said plate 103 is shown secured by a pair of conventional rotatable screw down clips 108, of which only one is shown.

25 The magnetic assembly 101 will have an identical arrangement.

30 In operation, the magnetic assemblies extend their fields through the underlying supporting member 99 to attract and retain onto the undersurface of said member 99 the metallic particles which are withdrawn from the material being processed within the grinding chamber.

35 When it is desired to clean out the accumulated metallic particles, the clips 108 are loosened and rotated 180 degrees. The magnetic assemblies are then swung upwardly to withdraw the force field sufficiently from the underlying surface of the member 99 to have the accumulated metallic particles drop into a suitable receptacle held thereunder.

40 Another modification is shown in FIG. 4 in which structure identical to what has been above described will be indicated by like reference characters.

45 The flange 30 carried on the rear wall 15 instead of having the projecting inverted V-shaped member 32 at its apex portion has a triangular post 112 cantilevered from said rear wall. The screen 113 differs from that previously described in having its upper ends secured together by an angled plate member 115 having bolts 116 extending therethrough. Said post 112 will the full width of the screen and provides hanger support for said screen.

50 The magnetic assemblies 100 and 101 overlie the screen directly as shown at either side thereof adjacent its apex. Here said assemblies are shown secured by said piano type hinges 106 to hangers 120 which will comprise transversely spaced pairs for each of said magnetic assemblies. Said hangers may be suitably secured as by welding to the top 20 of said housing.

55 The operation here is readily obvious from the description of the first modification.

60 Thus it is seen that there has been provided a simple and efficient apparatus for effectively removing metallic particles from material being processed within a grinding chamber. Said metallic particles are withdrawn very early in the grinding process of new material entering the grinding chamber before any damage can be caused by said particles. This apparatus has proved to be very satisfactory in performance.

65 It will of course be understood that various changes may be made in the form, details, arrangement and proportions of the parts, without departing from the scope of the invention herein which, generally stated, consists in an apparatus capable of carrying out the objects above set forth, in the parts and combinations of parts disclosed and defined in the appended claims.

What is claimed is:

1. An apparatus to collect metallic particles in connection with a grinding mill comprising a housing having

a grinding chamber therein having grinding means therein having in combination,

an andless screen structure comprising the side wall of said grinding chamber, said screen structure having a greater clearance with respect to the grinding means therein at its upper portion than at the remainder of its structure,

a non-magnetic plate member insert integral as a part of said screen structure adjacent the upper portion thereof and forming a wall portion thereof, and

a magnet overlying said plate member.

2. The structure set forth in claim 1, including

means securing said magnet,

said means comprising a hinge connecting said magnet and said screen for upward swinging movement of said magnet away from said screen.

3. The structure set forth in claim 1, including

a pair of hangers above said magnet depending from said housing, and

said hangers comprising means hinging said magnet thereto for swinging movement of said magnet away from said screen.
